RAILROAD CROSSING

Edward Sheehan, San Francisco, Calif.

Application August 26, 1936, Serial No. 98,001

3 Claims. (Cl. 246—273)

This invention relates to improvements in railroad crossings and has particular reference to means for eliminating noise and jar during the action of a car passing over the crossing.

5 A further object is to produce a device of this character which may be applied to any railroad crossing with a minimum amount of expense.

A further object is to produce a device of this character wherein the wheels of the vehicle will 10 have a broad bearing upon the face thereof which will be ample to carry the load, in counter-distinction to certain types of crossings, wherein the load is carried upon the flange of the wheel.

A further object is to produce a device of this 15 character which is automatic in its operation, irrespective of which direction the vehicle is moving over the crossing.

Other objects and advantages will be apparent 20 during the course of the following description.

In the accompanying drawings forming a part 25 of this specification and in which like numerals are employed to designate like parts throughout the same,

Fig. 1 is a top plan view of my improved crossing, having a portion thereof broken away;

Fig. 2 is a cross sectional view taken on the line 2—2 of Fig. 1;

Fig. 3 is a cross sectional view taken on the line 3—3 of Fig. 1, which is at right angles to 30 that of Fig. 2;

Fig. 4 is a cross sectional view taken on the line 4—4 of Fig. 1;

Fig. 5 is a top plan view of the actuating cam; and

Fig. 6 is a cross sectional view taken on the line 35 6—6 of Fig. 5 and looking in the direction of the arrow.

The ordinary railroad crossing permits flanged 40 wheels to pass over rails angularly disposed with relation to the rails upon which the wheels are travelling. Up to the present time, it has been customary practice, as far as applicant is aware, to provide a groove through the rail being crossed to accommodate for the flange of the wheel. This 45 construction means that not only will there be a groove through which the flange of the wheel must pass, but there will also be a groove in the rail upon which the wheel is travelling. Consequently, as the wheel travels over this groove, there will be a pounding action, which is of considerable force, particularly when the vehicle 50 upon which the wheel is mounted exerts heavy downward pressure. The result of keeping up crossings is very high as a result of this pounding action; and, therefore, I believe that with

the improvement of my device, this pounding action may be eliminated, thus saving excess cost of repairs, the cost of the jar on the rolling stock, and also eliminating the noise which is very objectionable, particularly in buildings close to the 5 crossing.

In the accompanying drawings wherein for the purpose of illustration is shown a preferred embodiment of my invention, the numerals 5 and 6 may be said to represent the east-west bound 10 tracks, while the numerals 7 and 8 may be said to represent the north-south bound tracks; and in the particular illustration of Fig. 1, these tracks are crossing each other at an angle of 90°. I propose to employ a bed plate 9, which may be 15 supported in any convenient manner, as by a supporting girder construction 11.

Referring now to Fig. 1, it will be noted that the rails 5 and 7 approach each other at right angles, and their ends are so sawed as to present a 45° surface 12. As the construction and operation of each one of the four corners of the crossing is exactly the same, further discussion will be confined to the corner toward the left of the drawing. Mounted upon the bed plate 9 are 20 rocker arms 13 and 14. These rocker arms are pivoted as at 16 and extend diagonally so that their ends are adjacent the diagonally positioned corners.

Pivoted to each end of each arm is a cam member 17, upon which are formed cams 19 and 21, the top of this cam member being flat, as shown at 22, the purpose of which will be later seen. At 23 I have shown a supporting member secured to the plate 9 and to which are pivoted, as at 26 and 27, pivoted rail sections 25 28 and 29 respectively. The ends of these rail sections 28 and 29 are bevelled, as shown at 31; and each rail section has its ends cut at an angle of 45° in each direction, so as to form a 90° angular point. The bevelled portion 31 rests upon the cam surface 21 when the cam members 17 are in 30 the position of Fig. 2 and rests upon the top of the cam members when the cams are in the position of Fig. 3. It is, of course, understood that similar pivoted rail sections 28 and 29 extend 35 between the other breaks in the rails 6, 7, and 8, and the end of each of these other pivoted rail sections overlies its respective cam members. At 40 32 I have shown a power lever pivoted to the rail 7 and having its free end in contact with one of the cam surfaces, for instance, the cam surface 21 of the cam member 17. A similar power lever is shown at 33, the same being pivoted to the rail 5 and having its free end overlying the cam surface 19 of the same cam member 17, it 45

50 55

being understood that there are two of these power levers adjacent each angle of the crossing.

The result of this construction is that assuming a train is proceeding from the north over the rails 7 and 8, the flanges of the wheels will engage the power levers 32 and 33, pivoting the free ends downwardly against the cams 17, mounted on the rocker arms 13 and 14. Immediately, these cams will be moved to the full line position of Fig. 1, forcing the cam member 17 to raise the pivoted sections 28 and 29 in the north-south bound track; and as the flat surface 22 and the cam surface 21 have passed from beneath the pivoted sections of the east-west rails, these sections will drop, as illustrated in Fig. 2, leaving a gap through which the flanges of the wheels may pass. Therefore, the wheels, in passing over the crossing, will be supported by a continuous rail surface, thus eliminating the jar and resultant damage above referred to.

It is, of course, obvious that a train passing from east or west, or vice versa will first engage its respective power levers, and the action will be identical, with the exception that the rocker arms will move in the opposite direction so that the cams will raise and support the east-west pivoted sections and release the north-south pivoted sections.

It is to be understood that the form of my invention herewith shown and described is to be taken as a preferred example of the same and that various changes relative to the material, size, shape, and arrangement of parts may be resorted to without departing from the spirit of the invention or the scope of the subjoined claims.

Having thus described my invention, I claim:—

1. In a railroad crossing of the character described, pivoted crossing sections forming continuations of the crossing rails, a pair of diagonally disposed rocker arms pivotally secured in said crossing, cam blocks carried by the ends of said rocker arms and underlying said pivoted rail sections, and pivoted power levers contacting said cams, whereby said power levers will actuate said cams when contacted by the flanges of wheels passing over said rails. 10

2. In a railroad crossing of the character described, pivoted crossing sections forming continuations of the crossing rails, a pair of diagonally disposed rocker arms pivotally secured in said crossing, cam blocks carried by the ends of said rocker arms and underlying said pivoted rail sections, and pivoted power levers contacting said cams, whereby said power levers will actuate said cams when contacted by the flanges of wheels passing over said rails, said power levers moving said cams from a point beneath the pivoted rail sections of said crossing extending in one direction to a point beneath the pivoted rail sections extending in another direction. 20

3. In a railroad crossing comprising parallel rails intersecting similar parallel rails, said rails having their meeting ends angularly cut, pivoted rail sections continuing said rails between the meeting ends, cam members disposed beneath the free ends of said pivoted members, said cam members being secured to rocker arms, and means for moving said rocker arms simultaneously by a train approaching said crossing so as to support the pivoted rail sections over which said train is to pass. 25

EDWARD SHEEHAN.
